(57) **CLAIM**

The ornamental design for a paint liner, as shown and described.

DESCRIPTION

FIG. 1 is a top perspective view of a paint liner showing our new design.

FIG. 2 is a top plan view thereof.

FIG. 3 is a left elevational side view thereof, the article being shown in a turned-over configuration.

FIG. 4 is a right elevational side view of what is shown in FIG. 3.

FIG. 5 is a front elevational view of what is shown in FIG. 3.

FIG. 6 is a rear elevational view of what is shown in FIG. 3.

FIG. 7 is a top perspective view thereof, the article being shown in a turned-over configuration and along a first orientation.

FIG. 8 is another top perspective view thereof, the article being shown in a turned-over configuration and along a second orientation; and,

FIG. 9 is a bottom plan view thereof.
